UNITED STATES PATENT OFFICE

147,889

DESIGN FOR A RADIATOR FAUCET OR
SIMILAR ARTICLE

John F. Carter, Bryan, Ohio

Application March 13, 1946, Serial No. 127,413

Term of patent 7 years

(Cl. D91—1)

To all whom it may concern:

Be it known that I, John F. Carter, a citizen of the United States and a resident of Bryan, in the county of Williams and State of Ohio, have invented a new, original, and ornamental Design for a Radiator Faucet or Similar Article, of which the following is a specification, reference being had to the accompanying drawing, forming part thereof.

Figure 1 is a plan view of a radiator faucet or similar article showing my new design.

Figure 2 is a side elevational view thereof, and
Figure 3 is a rear elevational view thereof.

I claim:

The ornamental design for a radiator faucet or similar article, substantially as shown.

JOHN F. CARTER.
